CLAIM

An ornamental design for a chair, as shown and described.

DESCRIPTION

FIG. 1 is a front perspective view of a chair.

FIG. 2 is a right-side view of the chair.

FIG. 3 is a left-side view of the chair.

FIG. 4 is a front view of the chair.

FIG. 5 is a rear view of the chair.

FIG. 6 is a top view of the chair; and,

FIG. 7 is a bottom view of the chair.

The shading is provided to illustrate contour only and is not an indication of texture, gloss, etc. The broken lines illustrate the portions of the chair that form no part of the claimed design.

The chair is shown with symbolic breaks in its height. The appearance of any portion of the article between the break lines forms no part of the claimed design.
